UNITED STATES PATENT OFFICE.

EDMUND B. KIRBY, OF NEW YORK, N. Y.

BLAST-FURNACE CONSTRUCTION.

Application filed February 16, 1920. Serial No. 358,970.

To all whom it may concern:

Be it known that I, EDMUND B. KIRBY, a citizen of the United States, residing at New York, in the county of New York and 5 State of New York, have invented a certain new and useful Improvement in Blast-Furnace Construction, of which the following is a full, clear, and exact description.

The present invention relates to blast furnaces and furnaces of similar nature.

The principal object of the invention is to provide a furnace in which the process or method which is set forth in my application Serial No. 358,969, filed Feb. 16, 1920, 15 may be carried out.

A further object of the invention is to provide a furnace having certain characteristic features which may be useful in connection with blast furnace construction for 20 purposes other than that of carrying out the particular method to which reference has before been made.

Additional objects of the invention will appear more at large as the description proceeds.

Reference should be had to the accompanying drawings forming a part of this specification, in which Fig. 1 is a sectional elevation of a furnace embodying my invention; Fig. 2 is a sectional elevation at right angles to the elevation of Fig. 1; Fig. 3 is a sectional elevation showing a portion of a furnace embodying a modified construction; Fig. 4 is a sectional plan view of a furnace 30 embodying the invention; Fig. 5 is an elevation with portions in section embodying a feature of construction of the furnace. Figs. 6 and 7 show two other forms of lower tuyères and Fig. 8 shows the nozzles of a 40 tuyère and a fuel injector.

The method of operating a blast furnace or similar furnace as set forth in my co-pending application embraces in general the method of feeding into the furnace the 45 material to be treated and the solid fuel such as coke or anthracite so that they will descend through the furnace as separate contacting columns. The material column is indicated at Fig. 2 and the fuel column at 50 Fig. 2. These columns contact with each other along a curved surface of equilibrium whose shape and position depend on the relative specific gravities of the material and the fuel and upon other factors; the surface 55 being at approximately the central zone of the furnace. The particles of the column

of fuel are made of smaller average size than the particles of the material column whereby the average interstices of the latter are larger and gases will ascend through the 60 column of material rather than the fuel column. An oxidizing blast is introduced at substantially the surface of contact between the columns of material and fuel, adjacent the lower end of these columns, and the 65 gases which are formed ascend substantially entirely through the column of material.

The process preferably proceeds in a manner to provide only a sufficient amount of combustion at the lower portion of the furnace to insure the formation of carbon monoxide. There is subsequently introduced into the columns of material at a higher elevation a supplementary oxidizing blast so that the carbon monoxide is burned 70 to carbon dioxide, thus liberating the remaining heat incident to the combustion of the fuel.

The method also contemplates the optional use of oxygen or air enriched with 80 oxygen in place of the usual air blast and further contemplates the use of fluid fuel or pulverulent solid fuel in localities where this is desirable, in which case such fuel is introduced along with the main blast.

The discharge opening of the tuyère which introduces the main blast is so located as to deliver the blast upon the fuel adjacent the plane of contact between the descending columns of charged material and solid fuel. 90 The supplementary blast, however, is delivered into the column of material so that it will not reach the fuel.

In form the furnace is preferably rectangular, although the shape may be varied 95 somewhat from this form so long as its shape permits the material and the fuel to be introduced in a manner to form the two contacting columns.

The material and the fuel are introduced 100 at a proper height by any of the well-known arrangements for charging, one of these being indicated at 5 in the drawings and the upper part of the furnace is provided with any of the well-known means for carrying 105 off the gases formed, but these are not illustrated inasmuch as they, like charging arrangements, are all well known in the art.

The main blast of the furnace may be introduced in any way which will enable it 110 to act upon the fuel at or near its contact with the column of material. In one mode

of construction the main blast tuyères of which one is indicated at 8 Fig. 2 and Fig. 8 are located along the fuel side wall of the furnace near its base and extend into the fuel column nearly to the contact. They are preferably adjustable in any well-known way for instance, the water-cooled tuyère 8 may be mounted in a sleeve 10 which has a ball and socket connection or fitting into the wall of the furnace, so that it may be moved slightly in an angular direction and also the tuyère 8 may be moved inwardly or outwardly in the sleeve 10. The tuyère 8 is connected by means of a pipe with a blast main 11. The nozzle of the tuyère opens downwardly to such an extent as to prevent the fuel from flowing into it. The velocity of the gas flow away from the nozzle and the non-conducting qualities of crushed fuel protect the nozzle. As before stated, there are a series of such tuyères which extend through the openings 9 in the wall of the furnace as indicated in Fig. 1.

In an alternative method of construction a single continuous tuyère is constituted by an inverted water-cooled trough 47 Fig. 6 extending between the end walls through the fuel column, near and parallel to its contact with the material column. This trough 30 constitutes a conduit which is connected to the blast main outside the furnace. Its continuous open bottom presents a large area for the blast to enter the interstices of the fuel while the fuel cannot flow up into the conduit.

A similar trough conduit serving as a tuyère may be constructed in the furnace wall alongside of the fuel column 49 Fig. 7. In this case the fuel column is narrowed as much as practicable as illustrated in the drawing, which shows the narrowing accomplished by a projection of the wall which permits the column to widen again below the tuyère.

Extending through the side wall of the furnace which is against the column of material and at an elevation above the zone of reduction are a series of auxiliary tuyères such as indicated at 29 Fig. 2 for the purpose of introducing the supplementary blast. Each tuyère is connected with a blast main 30. There may be more than one such row of auxiliary tuyères and such an additional row is indicated at 31.

As a part of the method for operating a blast furnace as set forth in my application as before mentioned, the main blast introduced near the base of the furnace is permitted to form carbon monoxide such as 50 may result from the temperature employed and this carbon monoxide is allowed to act upon the material as it descends through the zone of reduction above the main tuyères.

The formation of carbon monoxide liberates only one-third of the amount of

heat which would be evolved from the complete burning of the fuel. The carbon monoxide ascends through the interstices of the material column and after passing through the zone of reduction within which the carbon monoxide performs its necessary reactions with the material, and meeting with the auxiliary blast introduced through the row of tuyères 29 and additional rows of tuyères if they be used, the carbon monoxide is completely burned to form carbon dioxide thus liberating the remaining two-thirds of the heat incident to the combustion of the original fuel.

The auxiliary tuyères are introduced through the furnace walls so that the blast therefrom will enter the column of the charged material and not reach the column of fuel and as clearly explained in connection with the method set forth in my prior application, it is essential that the hot carbon dioxide gases ascend through the column of material and not through the column of fuel for if they did ascend through the latter the carbon dioxide would be reconverted to carbon monoxide by contact with the hot fuel.

Up to the present time the difficulties attending the use of injectable fuels in blast furnaces have either prevented or limited their applications and in most cases have overbalanced the advantages of such fuels. Since these difficulties are mainly due to pasty conditions affecting penetration, and to the chilling effect of injection upon the solid fuel, especially when oil or powdered coal is used, the open interstices and the diminution of nitrogen secured by my process, makes it now possible to evade such difficulties and to utilize all such fuels freely.

It may be explained that the injectable fuels to which I refer constitute a well-understood and clearly defined class distinguished by having the peculiar qualities necessary for combustion within the interstices of a blast furnace column.

Such fuel to be injectable must either be gaseous or be liquid or be a solid powdered finely. They must thus be capable of being scattered by the injection force into liquid globules or solid particles, which are small enough to be carried by the injection current through the fine interstices of a blast furnace column and to mix with the blast and to be consumed quickly by virtue of their small size, before choking these interstices.

For convenience, therefore, I shall refer to all such fuels as "injectable fuel."

In those cases where it is desired that the heat for smelting shall be supplied wholly or partly by fluid or pulverulent fuel instead of solid fuel the injection of this is made close to the lower blast which is to burn it. There are well-known and stand-

ard forms of injectors for each kind of these injectable fuels and I have therefore merely indicated by the pipe 12 and 13 Figs. 2 and 8 that when such fuel is required some suitable injector is preferably placed within the tuyère or delivering into it, thus affecting a delivery of this fuel with the blast.

In the inverted trough form of tuyère the fuel injection apparatus is placed along the 10 upper part of the conduit thus formed as at 48 Fig. 6, and 50 Fig. 7. This apparatus distributes the injectable fuel with the blast into the interstices of the solid fuel along the open bottom.

15 When all the smelting heat is supplied by injectable fuel the column of solid fuel is not consumed but serves through its open interstices and plane of contact, to transmit the gases of combustion past the zone where 20 the material, nearing its fusion point, becomes pasty and impermeable.

In those cases where injectable fuel is used therefore, it is desirable to provide 25 means for flowing off the solid fuel column so that it may have a regular descending movement which will maintain the surface of contact in the desired position. Moreover, even in the usual process of smelting with solid fuel only, it is desirable to have 30 such means for regulating the descent of the fuel column.

This is accomplished by means of a series of inclined discharge pipes or conduits such as indicated at 25. These conduits extend 35 through the wall of the furnace on the fuel column side and are preferably water-cooled. The passage of the fuel through the conduit is controlled by suitable valves 26 which are illustrated as a part of each conduit. These are simply gate valves which 40 may be opened to any desired degree to permit the passage of fuel. The conduits connect with a suitable conveyor mechanism which may be of any type desired such as a 45 screw conveyor located within the housing 27. The fuel which is thus drawn away is utilized by being re-charged in the upper part of the furnace.

For purposes of furnace manipulation a 50 series of ordinary tap holes 18 is indicated along the wall of the furnace at the hearth bottom.

To provide for the increased rapidity of fusion occurring in my process and the decreased storage space for molten products, 55 it has been important to provide means for the continuous removal of the molten products in place of the customary intermittent tapping.

60 Inverted siphon continuous flow taps have a very limited application at the present time because of the difficulties in starting and in keeping the tap channel hot or in opening a channel when it cools. The 65 present invention, therefore, provides a

means for maintaining the heat of the channel when the heat of the current becomes insufficient and also for heating the channel when the flow in it becomes frozen.

This means consists of arrangements for 70 electric resistance heating of the channel and this resistance heating makes it possible to utilize the inverted siphon continuous flow tap for any molten product.

In smelting some materials, the bottom of 75 the blast furnace hearth also chills occasionally, so as to obstruct the flow of products to the taps and for such work the same arrangements for electric resistance heating are provided or extended so as to maintain 80 a free channel along the hearth bottom to the tap or taps.

The resistance heating of either a tap channel or a hearth channel requires the 85 passing of an electric current along a suitable resistor which extends alongside or beneath the channel or which occupies it wholly or partly.

The material of the resistor must be adapted 90 to the particular products which are being made in each furnace and is therefore not restricted to any specific material. For instance, carbon or graphite may be used as the resistor material for heating the hearth or tap channels except in cases where 95 the molten product dissolves carbon or reacts with it. In such cases suitable resistor material other than carbon or graphite should be used.

Moreover, I do not restrict myself to any 100 particular current or means of causing it to traverse the resistor and have indicated two methods in the same drawing for purposes of illustration. In one of these the tap channel 17 Figs. 1 and 4 is partly constructed in an elongated mass of carbon which thus constitutes the sides and bottom 105 of the channel. By means of water-cooled electrodes at 20 and 22, a suitable current is passed along this carbon resistor.

The channel of flow 7 constructed in the sloping hearth bottom for convenience in receiving and leading the stream of molten products to one or both taps, in this case conceived as draining to the left-hand 110 tap, also has its sides and bottom composed of carbon. By means of the electrodes

22-23 a current may be sent through this carbon resistor or by the electrodes 20-23, the same current may heat both the tap 115 channel and the hearth channel. By extending this construction to the right-hand tap, the same current will heat both tap channels and the hearth channel. In Fig. 3 a carbon resistor 35 is shown laid along 120 the bottom of the tap channel and supplied with current through the electrodes 36 and 37.

The other method illustrated and which 125 is preferred for most cases is shown as ap-

plied to the right-hand tap only. Here a miniature electric induction furnace of any of the well-known types is employed to create the current through the resistor. The 5 illustration also shows the utilization of a furnace product for the resistor such as the metal from an iron blast furnace.

The resistor 40 Figs. 1-4-5 associated with the tap channel, has its ends connected 10 by a conductor 39-39 so as to make the resistor part of a rectangular conducting ring which constitutes the closed secondary circuit of an electric induction furnace transformer.

15 This closed ring of the secondary circuit, which ring may be of any convenient form, links through a closed core ring of iron which constitutes the magnetic circuit of the transformer. This iron ring may also 20 be of any convenient form and is shown as an upright rectangular ring 41 placed outside of the furnace walls.

The primary circuit is a conductor wound 25 for the required number of turns around any convenient part or parts of the iron core ring. It is indicated by one or both of the coil spools 42 which are placed outside of the furnace walls in positions protected from the tap hole heat. The various designs 30 of induction furnaces are well-known and I do not limit myself to any one type or construction.

An alternating current supplied to the 35 primary circuit coils induces a secondary alternating current of lower voltage within the rectangular closed secondary circuit 39-40 by which that portion of it constituted by the resistor 40 alongside of or within the tap channel, is brought to the necessary temperature thus heating the channel 40 and its contents.

The portion 40 of the secondary circuit associated with the channel to be heated, 45 may be of any suitable resistor material, fusible or infusible, while the rest of the circuit 39 may be of any conducting material, fusible or infusible, since it is not necessary to generate heat in this part of the circuit.

Where the blast furnace is used for the 50 production of iron, the metal product itself may conveniently constitute the entire secondary circuit as represented by 40-39. That is to say, this circuit may be formed by a rectangular ring pool of iron which is 55 molten when the furnace is in operation and yet when the furnace is shut down and subsequently started, the resistance of the solidified iron is sufficiently great to create the desired heat.

60 In this case the continuous flow of iron passes along that part 40 of the rectangular pool, which occupies the tap channel and overflows the dam 51 which retains the pool. This pool is shown with a greater conducting cross-section in those parts 39 of the

ring where conduction rather than heat generation is desired. If the tap is used for iron only the overflow dam is placed at such a height that the pool level will close the tap channel and trap the blast.

If it is desired to also pass the slag through the same tap the dam is placed low enough for the pool surface to stand below the top of the channel and leave a passageway for the slag stream. This stream is 75 kept from the iron overflow dam by the inverted dam 52 and passes over the slag overflow dam 16.

This arrangement for a two product tap 80 may also be utilized to handle a product like calcium carbide which has little conductivity when cold and which dissolves carbon. Here the light carbide, like the iron slag, will flow through the tap over a molten pool 85 of the heavy iron or such alloy of iron as is formed during operations and this pool is heated when required by passing an electric current through it. A small by-product of carbide smelting is usually some iron containing much silicon.

In first starting the furnace, ordinary iron would be inserted but this would gradually have its silicon contents raised to that of the furnace product passing through the pool. I therefore use the term "iron" here- 90 after without limiting myself as to its degree of purity for the reason that the composition of the metal is not material so long as it is heavier than the other product, is immiscible with it, does not evaporate too 95 fast at the temperature used and possesses electric conductivity enough when cold to heat up.

If a furnace produces no metal to displace the original filling, the latter will remain as 100 a permanent resistor for heating the slag or other light product flowing over it. It is obvious that a variety of metals and alloys have the aforesaid qualities to such an extent that they may be thus utilized as permanent pool resistors for suitable light products flowing over them and I do not restrict myself to any one.

110 It will be understood that after the furnace has been started and while in its normal operation the continuous flow of molten products through the tap openings will of itself maintain the channels in open condition so that the electric heating is not needed during such normal operation but is only 115 required in an emergency or to be employed for a short time at starting or during occasional interruptions or irregularities which are inevitable in blast furnace operations.

120 It therefore follows that the cost of this electric heating will be but a small item.

Having described my invention, I claim:

1. A blast furnace having an interior space adapted to permit the maintenance of separate descending contacting columns of 125

material to be treated and solid fuel, and a tuyère so placed as to discharge upon the fuel substantially at its surface of contact with the material column.

5 2. A blast furnace having an interior space adapted to permit the maintenance of separate descending contacting columns of material to be treated and solid fuel, and a tuyère so placed as to discharge into the fuel 70 near its surface of contact with the material column.

10 3. A blast furnace having an interior space adapted to permit the maintenance of separate descending contacting columns of 75 material to be treated and solid fuel, a tuyère so placed as to discharge upon the fuel substantially at its surface of contact with the material column, and an auxiliary tuyère at an elevation above the zone of reduction and so placed that its blast will enter the material without impinging upon the fuel column. 80

15 4. A blast furnace having an interior space adapted to permit the maintenance of 85 separate descending contacting columns of material to be treated and solid fuel, a tuyère so placed as to discharge into the fuel near its surface of contact with the material column, and an auxiliary tuyère at an elevation 90 above the zone of reduction and so placed that its blast will enter the material without impinging upon the fuel column.

20 5. A blast furnace having an interior space adapted to permit the maintenance of 95 separate descending contacting columns of material to be treated and solid fuel, a tuyère so placed as to discharge upon the fuel substantially at its surface of contact with the material column, and means of injecting injectable fuel with the blast. 100

25 6. A blast furnace having an interior space adapted to permit the maintenance of 105 separate descending contacting columns of material to be treated and solid fuel, a tuyère so placed as to discharge into the fuel near its surface of contact with the material column, and means of injecting injectable fuel with the blast. 110

30 7. A blast furnace having an interior space adapted to permit the maintenance of 115 separate descending contacting columns of material to be treated and solid fuel, a tuyère so placed as to discharge upon the fuel substantially at its surface of contact with the material column, an auxiliary tuyère at an elevation above the zone of reduction and so placed that its blast will enter the material without impinging upon the fuel column, and means of injecting injectable fuel with the main blast. 120

35 8. A blast furnace having an interior space adapted to permit the maintenance of 125 separate descending contacting columns of material to be treated and solid fuel, a tuyère so placed as to discharge into the

fuel near its surface of contact with the material column, an auxiliary tuyère at an elevation above the zone of reduction and so placed that its blast will enter the material without impinging upon the fuel column, and means of injecting injectable fuel with the main blast. 70

9. A blast furnace having an interior space adapted to permit the maintenance of 75 separate descending contacting columns of material to be treated and solid fuel, a tuyère consisting of an inverted water-cooled trough extending horizontally through the fuel column near and parallel to its contact with the material column. 80

10. A blast furnace having an interior space adapted to permit the maintenance of 85 separate descending contacting columns of material to be treated and solid fuel, a tuyère consisting of a blast conduit extending horizontally along the fuel wall of the furnace having its discharge opening practically continuous alongside the fuel column parallel to its contact with the material column, said opening being directed sufficiently downward to prevent the inflow of fuel. 90

11. A blast furnace having an interior space adapted to permit the maintenance of 95 separate descending contacting columns of material to be treated and solid fuel, a tuyère so placed as to discharge into the fuel near its surface of contact with the material column and having a discharge opening directed sufficiently downward to prevent the inflow of fuel, and means within said tuyère for injecting injectable fuel with the blast. 100

12. A blast furnace having an interior space adapted to permit the maintenance of 105 separate descending contacting columns of material to be treated and solid fuel, a tuyère for introducing the blast, a sufficient opening below the tuyère for the solid fuel to flow out of the furnace, and a fuel conduit of sufficient length to prevent escape of blast and means for regulating said flow. 110

13. A blast furnace having an interior space adapted to permit the maintenance of 115 separate descending contacting columns of material to be treated and solid fuel, a tuyère for introducing the blast, means of injecting injectable fuel with the blast, a sufficient opening below the tuyère for the solid fuel to flow out of the furnace, and a fuel conduit of sufficient length to prevent escape of blast and means for regulating said flow. 120

14. A metallurgical furnace having a tap whose channel has a cross section small compared to its length, an overflow dam so placed as to retain within this channel an elongated pool of resistor metal whose surface is sufficiently below the channel top to maintain a passageway for a stream of furnace product, said metal having electrical conductivity when cold, a boiling point 125 130

above the temperature of said molten product and being heavier than and immiscible with it, one terminal of an electric circuit being in contact with the outside end of 5 said metal pool and the other terminal with the end inside of the furnace and means for passing a current through said circuit.

15. A metallurgical furnace having a tap composed of two through channels from the 10 inside to the outside of the furnace, one of these having a cross section which is small compared with its length, the inner ends of these through channels being joined together by a cross channel and the outer 15 ends by another cross channel, an overflow dam so placed as to retain in said channels a permanent pool of the product being discharged and this pool constituting the secondary circuit of an electric induction furnace 20 transformer.

16. A metallurgical furnace having a tap, a resistor associated with the channel of said tap composed of one of the products from the furnace operation, an overflow 25 dam retaining said resistor in a pool of such shape as to constitute a closed circuit which is the secondary circuit of an electric induction furnace transformer, the surface of said pool being sufficiently below the top of 30 said channel to leave passageway for a second molten product, and an inverted dam so placed as to pass the lower product and divert the upper product.

17. A metallurgical furnace having an inverted siphon continuous tap, a resistor associated with the channel of said tap composed of one of the products from the furnace operation, an overflow dam retaining said resistor in a pool of such shape as 40 to constitute a closed circuit which is the secondary circuit of an electric induction furnace transformer, the surface of said pool being sufficiently below the top of said channel to leave passageway for a second 45 molten product, and an inverted dam so placed as to pass the lower product and divert the upper product.

18. A blast furnace having an inverted siphon continuous tap, an infusible, insoluble resistor reaching from the inside to the outside of the furnace, and so placed along the channel of said tap as to be in continuous contact with the stream passing through it, terminals of an electric circuit connected 50 to the inside and outside ends of said resistor and means for passing an electric current through it.

19. A blast furnace having an inverted siphon continuous tap, the channel of which has a cross section small compared to its 60 length, an overflow dam so placed as to keep the channel filled with a permanent pool of the product being discharged, an electric conductor having one terminal in contact with the outside end of the pool and 65 the other with the end inside of the furnace and forming with said pool a closed circuit which constitutes the secondary circuit of an electric induction furnace transformer.

20. A blast furnace having in its hearth 70 bottom a contracted channel of flow connecting with the channel of an inverted siphon continuous tap, the cross section in each channel being small in comparison with its length, an overflow dam so placed as to create a permanent pool of the molten product occupying the continuous channel thus formed by the two channels aforesaid, an electric circuit having its terminals in contact with the opposite ends of this pool and 75 means for passing a current through the circuit.

21. A blast furnace comprising a chamber with means at the top for introducing the material to be treated and its solid fuel, 80 said chamber having a horizontal cross-section which is approximately rectangular and of such proportions as to permit the maintenance of separate columns of material and fuel, and a blast tuyère near the base 85 of the chamber consisting of an inverted water-cooled trough so placed as to extend horizontally through the fuel column parallel to its contact with the material column and connected with the blast.

22. A blast furnace comprising a chamber with means at the top for introducing the material to be treated and its solid fuel, said chamber having a horizontal cross-section which is approximately rectangular and of such proportions as to permit the maintenance of separate columns of material and fuel, a blast tuyère near the base of the chamber consisting of an inverted water-cooled trough so placed as to extend horizontally through the fuel column parallel to its contact with the material column and connected with the blast and means for injecting injectable fuel placed within said inverted trough.

In testimony whereof, I hereunto affix my signature.

EDMUND B. KIRBY.
